US0D1046631S

(12) **United States Design Patent** (10) **Patent No.:** **US D1,046,631 S**
(45) **Date of Patent:** **** Oct. 15, 2024**

(54) **WATCH**

(71) Applicant: **Shenzhen Chilong Industrial Co., Ltd.**, Shenzhen (CN)

(72) Inventor: **Xiaowen Li**, Shenzhen (CN)

(73) Assignee: **Shenzhen Chilong Industrial Co., Ltd.**, Shenzhen (CN)

(**) Term: **15 Years**

(21) Appl. No.: **29/853,933**

(22) Filed: **Sep. 20, 2022**

(30) **Foreign Application Priority Data**

Sep. 9, 2022 (CN) 202230598353.1

(51) **LOC (14) Cl.** **10-02**

(52) **U.S. Cl.**

USPC **D10/38; D10/32**
